DOUBLE-ACTING HINGE FRAME

Clemens W. Kujawa, Cudahy, Wis.

Application August 18, 1950, Serial No. 180,110

1 Claim. (Cl. 16—147)

1

This invention appertains to swinging closures and more particularly to a novel door structure, whereby the door can be opened from either side of an opening and is an improvement over my Patent No. 2,511,777, issued to me June 13, 1950.

One of the primary objects of my present invention is to provide novel means for mounting a door to permit the opening thereof from either side of an opening, the structure being such that a heavy door, such as the insulated door of a refrigerator, can be effectively supported against sagging from both sides thereof.

Another salient object of my invention is to provide a novel structure for a double hung door, whereby the active size of the door opening is not diminished and whereby a close fit can be had between the door and door frame, and whereby the door and/or frame can readily be provided with insulating strips or gaskets should the door be for a refrigerator.

A further object of my invention is the provision of a one piece relatively thin metal frame plate having an opening therein corresponding exactly to the size of the door opening and adapted to set flat against the door frame or around the door opening, the frame plate being hingedly connected along one entire vertical edge to the frame or refrigerator, and the opposite edge of the frame plate, having hingedly connected thereto along the entire length thereof, the closure door, whereby either the door or frame plate can be swung open on the door frame or refrigerator as a unit on one side of the opening, or the door can be swung open alone on the frame plate on the other side of the door opening.

A further object of my invention is the provision of means whereby the frame plate can be detachably latched to the door frame or refrigerator against accidental swinging movement and whereby the door can be detachably latched to the frame plate against accidental swinging movement.

A still further object of my invention is to provide an improved door structure of the above character, which will be durable and efficient in use, one that will be simple and easy to manufacture and one which can be placed upon the market at a low cost.

With these and other objects in view, the invention consists in the novel construction, arrangement and formation of parts, as will be hereinafter more specifically described and claimed and illustrated in the accompanying drawing, in which drawing:

2

Figure 1 is a front elevational view of a refrigerator equipped with my improved door structure, the door being shown swung open on its frame plate.

Figure 2 is a fragmentary horizontal sectional view taken on the line 2—2 of Figure 1, looking in the direction of the arrows.

Figure 3 is a view similar to Figure 2, but showing the door and the frame plate swung open on the refrigerator as a unit.

Figure 4 is a detail vertical sectional view taken on the line 4—4 of Figure 2, looking in the direction of the arrows, illustrating the latch for connecting the frame plate with the door frame or refrigerator.

Figure 5 is a detail vertical sectional view taken on the line 5—5 of Figure 3, looking in the direction of the arrows, illustrating the latch for detachably connecting the door to the frame plate.

Figure 6 is an exploded view showing the frame plate and the hinges prior to the forming of the hinge barrels and parts of the latches.

Referring to the drawing in detail wherein similar reference characters designate corresponding parts throughout the several views, the letter D generally indicates my improved door structure as a whole which can be utilized in connection with any door or window opening or the like. For the purpose of illustration, I have shown my door structure D incorporated with a refrigerator R.

The refrigerator R per se forms no part of the present invention and can be of the usual character now found in the open market and can be provided with the usual body 10, having the main opening 11 to permit access to be had to the interior of the refrigerator. The body of the refrigerator can be provided with an upper freezing compartment 12 and shelves 13.

The improved door structure D comprises a door 14 and a door frame plate 15.

The door 14 can also be of any desired character and of a size and shape to entirely close the opening 11, and in the case of a refrigerator, the door 14 can be insulated in any desired way. The door frame plate 15 is preferably formed from relatively thin sheet metal material and is shaped to set flat against a door frame around the opening and is of such a size so as to correspond exactly with the size of the door opening 11.

One vertical edge of the frame plate 15 is connected at one side of the door frame or opening 11 by a piano type hinge 16, and it is to be noted that the hinge extends substantially the entire

height of the frame plate 15. This is for the purpose of providing an adequate hinge support. The opposite vertical edge of the door frame 15 is hingedly connected to the door 14 by means of a piano type hinge 17, and it is to be noted that this hinge extends the entire height of the frame plate 15, and the door 14 so as to prevent sagging of the door 14. The hinges 16 and 17 can be formed in any desired way, and as illustrated in Figure 6, hinge barrels 18 can be formed on the opposite vertical edges of the frame plate 15 if so desired, and obviously, the hinge leaf 19 for the hinge 16 can be riveted or otherwise fastened to the refrigerator and a hinge leaf 20 for the hinge 17 can be riveted or otherwise fastened to the edge of the door 14. If preferred, a hinge leaf can be riveted or otherwise secured to frame 15 instead of forming the hinge barrels 18 directly on the frame.

From the description so far, it can be seen that the door 14 when it is closed will fit flat against the frame plate 15 and leakage around the door and the frame plate and between the frame plate and the door frame will be reduced to a minimum. Likewise, suitable gaskets can be utilized around the door and the frame plate 15.

Considering that the door 14 is in its closed position, then the door can be swung open on the hinge 17 at one side of the door opening or refrigerator R, as shown in Figure 2. If it is more convenient to open the door from the other side, and considering that the door 14 is in its closed position, then the frame plate can be swung open on the hinge 16 carrying the door 14 therewith, as shown in Figure 3 of the drawing.

One of the important features of my invention is the provision of means whereby the frame plate 15 can be detachably latched to the refrigerator body or door frame, and whereby the door 14 can be detachably latched to the frame plate. Any desired type and character of latches can be utilized, and one preferred type of latch for the frame plate and for the door and frame plate has been illustrated. Referring more particularly to Figures 2 and 4, the frame plate 15 on the 45

opposite side thereof from the hinge 16 can be provided with an inwardly directed resilient latch arm 21, and this latch arm can be formed directly from the frame plate 15. A keeper 22 can be secured to the door frame or the refrigerator, and when the latch arm engages the keeper 22, the frame plate 15 will be detachably connected to the refrigerator.

To detachably latch the door 14 to the frame plate 15, the frame plate 15 on the opposite side thereof from the hinge 17 is provided with an inwardly directed arm 23 carrying a keeper 24 for receiving the latch nose 25 rigidly secured to the door 14 adjacent to the edge which is remote from the hinge 17.

It can be seen that when it is desired to swing open the door 14 on the frame plate 15, that the door is grasped, and obviously, the door can be provided with a hand grip at this point, adjacent to its edge remote from the hinge 17, an opening movement will not affect the hinge 16 but will permit the free opening of the door. When the door and door frame is grasped at the edge remote from the hinge 16, then the door and door frame can be swung open as a unit.

Various changes in details may be made without departing from the spirit or the scope of the invention, but what I claim as new is:

In a double hung door structure for refrigerators and the like, an open frame plate adapted to fit flat against a refrigerator around its door opening, hinge barrels formed on the opposite outer vertical edges of the frame plate, and a latch arm and a latch support formed on the inner vertical edges of the frame plate.
